UNITED STATES PATENT OFFICE.

THOMAS GORDON EDMONDSON, OF TARPON SPRINGS, FLORIDA.

SKEG ATTACHMENT FOR VESSELS.

SPECIFICATION forming part of Letters Patent No. 352,682, dated November 16, 1886.

Application filed April 12, 1886. Serial No. 198,375. (No model.)

To all whom it may concern:

Be it known that I, THOMAS GORDON EDMONDSON, of Tarpon Springs, in the county of Hillsborough and State of Florida, have invented a new and Improved Skeg Attachment for Vessels, of which the following is a full, clear, and exact description.

My invention consists in the construction and arrangement of parts, as hereinafter described and claimed.

In the accompanying drawings, Figure 1 is a side elevation of a yacht's hull provided with my improvement; and Fig. 2 is a longitudinal sectional elevation of the rear part of the same, showing my improvement in section.

The hull A has a sloping stern, B. The triangular skeg-casing D is attached beneath the latter. It has vertical sides E E', and its rear end is formed by the upright F, to which the rudder M is hinged at L. Said upright passes through and is fixed in the stern B, in order to give due rigidity to the skeg-casing and provide a secure attachment for the rudder.

The bottom of the casing D is in line with the keel, so that it draws no more water than the hull proper. Within the casing the triangular skeg H is pivoted at its front end. It

is raised and lowered by a chain, J, running through the tube K.

In Fig. 2 the skeg H is shown drawn up and housed in the casing D, and in Fig. 1 it is shown let down for use in guiding the yacht.

My improved skeg attachment is distinguished by these advantages: First, it occupies waste space, and the hull is not pierced nor weakened at any point where there is space available for stowage of cargo, &c.; second, the skeg-casing is so secured that it serves also as a firm point of attachment for the rudder; third, it does not come below the line of the keel, and will hence clear or pass whatever the latter does.

What I claim is—

In combination with the sloping stern B, the skeg-casing D, having its bottom aligned with the keel and its rear end formed by the upright or post F, which is secured in the extremity of the hull, and the triangular skeg H, pivoted at its front end within the like-shaped casing, all as shown and described.

THOMAS GORDON EDMONDSON.
